HEATING APPARATUS

Application filed June 6, 1929. Serial No. 368,896.

The present invention relates to heat transference apparatus of the class employed for the heating of a fresh fluid by extraction of heat from a hot, waste fluid. More particularly, the invention relates to an apparatus for preheating fresh water for laundry use by the extraction of heat from hot, waste water discharged from the laundry machinery. Important objects of the invention 5 are to provide a preheater of maximum efficiency; and to provide such an apparatus embodying improved features of design which render it extremely compact in comparison with its capacity for heat transfer- 10 ence. Other objects of the invention will appear hereinafter.

In the drawings:

- Fig. 1 is a side elevation of the apparatus;
- Fig. 2 is a plan view partly in section;
- Fig. 3 a transverse section taken on the line 3—3 of Fig. 1;
- Fig. 4 a section taken on the line 4—4 of Fig. 1;
- Fig. 5 a section taken on the line 5—5 of Fig. 1;
- Fig. 6 a section taken on the line 6—6 of Fig. 1; and

Fig. 7 a diagrammatic perspective view of the apparatus, with the parts separated, and 20 the passage of the fluids indicated.

My apparatus includes a central or intermediate shell 1, preferably considerably elongated and of cylindrical form, and two short end shells 2 and 3. These three shells are directly jointed together in axial alignment and are supported in a horizontal position or substantially so, by feet or pedestal members 4 which are fixed to the shell 1. Together with interior fluid-circulating means, to be described presently, these assembled shells form a preheating unit.

The ends of shell 1 are tightly closed by walls or cylinder heads 5 and 6. Within this shell are two central intersecting partitions 45 7 and 8 which divide the cylindrical space longitudinally into four elongated chambers or passages. Partition 7 is disposed horizontally and partition 8 is vertically disposed. Their intersection is at the axis of the shell and both extend the full diameter of the in-

terior space, so that the cross section of each of said chambers or passages is a quadrant. The partitions are solid and impervious to water and they are rigidly supported in place in any suitable manner. The four chambers 55 or passages separated thereby are designated 9, 10, 11 and 12. At one end, 7^a, horizontal partition 7 makes a water-tight fit across its full width with the end wall 5. At its opposite end, 7^b, only half the width of the partition reaches to the end wall 6 and makes a water-tight fit with it. This half of said width, disposed at the left of the vertical partition 8, (with reference to Figs. 3 to 6) terminates short of the end wall to provide 60 a fluid communication 13 of liberal capacity between the lower chamber 10 and the chamber 11 directly over it. The vertical partition 8, at one end, 8^a, makes a water-tight fit against the end wall 6 across its full width, 70 while its opposite end, 8^b, terminates, across its full width, short of the end wall 5 to provide two transverse horizontal fluid communications 14 and 15 of liberal capacity located respectively above and below the horizontal partition 7 and separated thereby. Communication 14 is between the lower chambers 9 and 10 and communication 15 is between the upper chambers 11 and 12. Their purpose will appear hereinafter.

A large number of water conduit tubes or pipes 16 extend throughout the length of the shell 1 and are arranged in four banks, one bank in each of the quadrant-shaped chambers. The four banks are designated 17, 18, 19 and 20. At their opposite ends all of the tubes are secured in apertures 21 formed in the end walls 5 and 6 and open therethrough into the end shells or sections 2 and 3. The 85 number, size and arrangement of the tubes are such as to leave a liberal water conduit space entirely surrounding them in each chamber. Opening into said conduit space of the lower chamber 9 is a water inlet nozzle 22, which extends downwardly from the shell and is flanged at its lower end. A water outlet nozzle 23 opens outwardly from the conduit space 12 located directly over chamber 9. The said outlet and inlet are both 90 100

located at the end of the shell 1 adjacent the wall 6.

A series of central baffle plates 24 are mounted in positions spaced along the axis 5 of the shell 1. Midway between these plates are mounted larger circular baffle plates 25 which fit within the circumference of the shell space. The central plates 24 are square in contour in the present instance and each 10 plate 25 is formed with a square central opening 26 of liberal area. The contour of plates 24 and of openings 26 may, of course, be varied. The plates of both series extend equally into all four chambers of the shell and the 15 tubes 16 pass through them.

For joining together the shells 1, 2 and 3, said shells are provided with rigid, annular end flanges 27 which abut and are secured together by bolts 28. The outer end of each 20 end shell is closed by a hinged cylinder head or door 29 which is held normally closed by bolts 30 passed through the projecting edge of the door and through a rigid flange 31 upon the outer edge of the shell.

25 Within the end shell 2 a horizontal central partition 32 is formed or rigidly mounted. This partition extends diametrically clear across the shell and also the full depth or length thereof. Its end edges make a water-tight fit with the end wall 5 of the shell 1 and with a horizontal, inwardly extending rib 33 formed upon the door 29. The partition divides the end shell space into an upper compartment 34 and a lower compartment 35. The former places the tubes of the two upper 30 banks 17 and 18 in transverse horizontal communication and the latter places the two lower banks 19 and 20 in transverse horizontal communication. The opposite end shell 3 is similarly provided with a central vertical partition 36 extending diametrically the full height and length of the shell. This partition divides the shell space into two compartments; and a horizontal, radially extending partition 37 extends between partition 36 and one side of the shell and subdivides one of said compartments into halves, forming an upper section 38 and a lower section 39. The undivided compartment is 40 designated 40. Both partitions make a water-tight fit at their opposite edges, with the end wall 6 of shell 1 and with inwardly extending ribs 33^a formed upon the door 29. The compartment sections 38 and 39 are in 45 alinement with the chambers 9 and 12, respectively, so that section 38 opens into upper bank of tubes 17, and lower bank 20 opens into section 39. Shell 3 is provided with an inlet nozzle 41 opening into the upper compartment section 38 and an outlet nozzle 42 opening into the lower compartment section 39. These nozzles extend respectively upwardly and downwardly and are flanged at their outer ends. Compartment 40, which is undivided, forms a transverse vertical commu-

nication between upper bank of tubes 18 and lower bank 19.

In the employment of the apparatus for preheating water for laundry use, hot, waste water from which heat is to be extracted is conducted from the laundry machinery to the inlet 41 of the preheating unit. From said inlet the waste water flows, as indicated by the arrows marked "W", into compartment section 38 and thence in succession through the upper bank 17 of tubes, the transverse horizontal communication formed by compartment 34 of the end shell 2, through the upper bank 18 of tubes, downwardly through the vertical communication formed by the compartment 40 of the end shell 3, through the lower bank 19 of tubes, the transverse communication formed by compartment 35 in end shell 2, and through the remaining lower bank 20 of tubes to the outlet 42 through which it leaves the apparatus. Simultaneously, the fresh water which is to be heated or preheated is conducted to the inlet 22 through which it flows directly into elongated lower chamber 9 of the shell. Thence the fresh water flows, as indicated by the arrows "F", along chamber 9, through the transverse horizontal communication 14 at the end of partition 8 to lower chamber 10, along the length of the latter and through the transverse vertical communication 13 at the end of horizontal partition 7, and into upper chamber 11, then along chamber 11, through transverse horizontal communication 15 at the end of vertical partition 8, into upper chamber 12 and along chamber 12 to outlet 23, through which it leaves the shell 1. In its passage through the conduit space of each chamber, surrounding the waste water pipes, the fresh water is diverted transversely by the baffle means and caused to travel in a serpentine path so as to direct its volume into a more effective contact with the heated pipes and obtain a more efficient transference of the heat. The baffle means are designed to do this with a minimum resistance to the flow of the fresh water. The central plates 24 and the larger, centrally apertured plates 25, materially spaced from plates 24, cause scarcely any friction in the water flow and do not appreciably cut down the head which forces the fresh water through the device.

The waste water descends through the device, becoming gradually cooler as it progresses through the various passages, while the fresh water ascends and becomes correspondingly warmer as it progresses through the various elongated chambers. The waste water passes through the tubes contained in the chambers 12, 11, 10 and 9 in the order named, whereas the fresh water passes through said chambers in the reversed order, that is 9, 10, 11 and 12, and constantly in a reverse direction to the flow of the waste water. This counter flow is very advan-

tageous as it greatly increases the efficiency of the heat transference. The fresh water, as it is heated, constantly progresses toward an approaching stream of warmer fluid so that a substantially constant thermal differential is maintained throughout the entire passage of the fresh water through the device. Furthermore the passageways of both fluids are designed for an unimpeded flow thereof at a rather high uniform velocity.

This also contributes materially to an efficient heat transference owing to the fact that the transference of heat from a fluid is in direct proportion to the velocity of its flow.

15 The preheater is designed throughout to give it the utmost efficiency and at the same time render it extremely compact in comparison with its heating capacity. It is designed also to facilitate its care. All passages 20 through which the dirty, waste water passes are readily accessible for cleansing. Opening of the doors 29 exposes the interiors of the end shells 2 and 3 and also all of the tubes 16 which serve as conduits for the 25 waste water, so that the tubes may be blown out. Furthermore the design of the entire preheater unit is such that all of its parts may be easily manufactured and assembled. If a particular service requires it, several of 30 the preheater units may be connected together in series by superposing them and joining their proper inlets and outlets. With reference to Fig. 1 for example, a similar preheating unit may be operatively connected 35 to the one shown by disposing it above the latter and joining the nozzles 22 and 42 of the upper unit to the nozzles 23 and 41 respectively of the lower unit. The flanged nozzles are designed and located to provide 40 for this. While the apparatus is shown as supported by pedestals, it may be suspended if found more convenient.

While I have shown a highly satisfactory form of my invention I do not wish to be limited strictly to the structure disclosed nor to the specific use stated but reserve the right to make such changes in both structure and application as will be within the scope of the claims.

50 What I claim is:

1. A heating apparatus comprising a substantially horizontal, tubular shell; a vertical partition and a horizontal partition both extending longitudinally through said shell and dividing it into a plurality of upper chambers located above the horizontal partition and a plurality of lower chambers located below the horizontal partition; a bank of fluid conduits extending longitudinally through each of 55 said chambers and leaving surrounding conduit space therealong in each chamber; fluid connections between the chambers; fluid connections between the different banks of conduits; outlet and inlet ports for the chambers; 60 and outlet and inlet ports for the conduits,

said ports and fluid connections of the chambers and conduits being designed and located to cooperate for a counterflow of fluids, one fluid first through the upper banks of conduits in succession and then through the lower 70 banks of conduits in succession, and the other fluid first through the lower chambers in succession and then through the upper chambers in succession constantly in a direction counter to the flow of the first fluid.

2. A heating apparatus comprising an elongated, tubular intermediate shell closed at its ends; a pair of shorter end shells mounted at the ends of said intermediate shell and closed at their outer ends; a horizontal partition and a vertical partition extending longitudinally through the intermediate shell and dividing its space into a pair of upper chambers and a pair of lower chambers; a bank of conduits extending longitudinally through each of said chambers, opening through the end walls of the intermediate shell into the end shells and leaving surrounding conduit space therealong in each chamber; a horizontal central partition dividing the interior of one end shell into an upper compartment opening into the two banks of upper conduits and a lower compartment opening into the two banks of lower conduits; a transverse fluid connection between said upper chambers; a transverse fluid connection between said lower chambers, both within the intermediate shell at the end thereof adjacent said divided end shell and separated from each other; a vertical partition dividing the interior of the opposite end shell into two compartments; a horizontal partition subdividing one of said latter compartments into an upper section communicating with one of the upper banks of conduits and having a fluid inlet therefor, and a lower section communicating with the lower bank directly beneath it and having a fluid outlet therefor, the intermediate shell having a fluid inlet and a fluid outlet adjacent said compartment sections and opening respectively into the lower and upper chambers adjacent said sections, and the undivided compartment alining with the two remaining chambers to communicate with the conduits of both; and a fluid connection between the latter chambers within the intermediate shell and adjacent said undivided compartment.

3. A heating apparatus comprising a substantially horizontal tubular shell closed at its ends; a central, longitudinally extending, horizontal partition in said shell; a central, longitudinally extending, vertical partition in said shell, said partition dividing the interior of the shell into four elongated chambers, the vertical partition terminating short of one of the end walls of the shell both above and below the horizontal partition to place the two upper chambers in communication with each other and the two lower chambers in commu- 120 125 130

- nication with each other and the opposite end of the horizontal partition terminating short of the opposite end wall, at one side only of the vertical partition to place an upper chamber into communication with the chamber directly beneath it; a bank of conduits extending longitudinally through each chamber and leaving a surrounding conduit space therealong in each chamber; transverse fluid communications between said banks of conduits; an outlet and an inlet for the chambers; and an outlet and an inlet for the conduits, said communications and said outlets and inlets of the chambers and the conduits being designed and located to cooperate for the flow of one fluid through the different banks of conduits in succession and the flow of another fluid in an opposite direction through the chambers in succession.
4. A heating apparatus comprising a tubular shell closed at its ends; a central, longitudinally extending, horizontal partition in said shell; a central, longitudinally extending, vertical partition in said shell, said partitions dividing the interior of the shell into four elongated chambers, the vertical partition terminating short of one of the end walls of the shell both above and below the horizontal partition to place the two upper chambers in communication with each other and the two lower chambers in communication with each other and the opposite end of the horizontal partition terminating short of the opposite end wall, at one side only of the vertical partition to place an upper chamber into communication with the chamber directly beneath it; a bank of conduits extending longitudinally through each chamber and leaving a surrounding conduit space therealong in each chamber; transverse fluid communications between said banks of conduits; an outlet and inlet for the chambers; an outlet and an inlet for the conduits, said communications and said outlets and inlets of the chambers and the conduits being designed and located to cooperate for the flow of one fluid through the different banks of conduits in succession and the flow of another fluid in an opposite direction through the chambers in succession; a series of central baffles spaced along the axis of the shell and extending transversely into each chamber; and a series of longitudinally spaced baffles alternating with said central baffles extending transversely inward from the walls of the shell and formed with openings of liberal area along the shell axis.
5. A heating apparatus comprising an elongated tubular intermediate shell closed at its ends; a pair of longitudinal partitions dividing the interior of said shell into quadrant chambers; four banks of tubes, each bank extending longitudinally through one of said chambers, leaving a surrounding conduit space in the latter and opening through

the closed ends of the shell; a fluid inlet for one of said chambers; a fluid outlet for another one of the chambers; transverse passages within the shell at opposite ends thereof cooperating with the partitions for a flow of fluid longitudinally through all the chambers in succession from the inlet to the outlet; end shells attached to the intermediate shell and having the tubes of the four banks opening into them; and partitions in said end shells dividing the latter into chambers forming transverse passages connecting the banks similarly to the chambers in which they lie for a flow of fluid longitudinally through all of the banks in succession in a reverse direction to the flow through the chambers.

6. A heating apparatus comprising an elongated tubular intermediate shell closed at its ends; a pair of longitudinal partitions dividing the interior of said shell into quadrant chambers; four banks of tubes, each bank extending longitudinally through one of said chambers, leaving a surrounding conduit space in the latter and opening through the closed ends of the shell; a fluid inlet for one of said chambers; a fluid outlet for another one of the chambers; transverse passages within the shell at opposite ends thereof cooperating with the partitions for a flow of fluid longitudinally through all the chambers in succession from the inlet to the outlet; end shells attached to the intermediate shell and having the tubes of the four banks opening into them; partitions in said end shells dividing the latter into chambers forming transverse passages connecting the banks similarly to the chambers in which they lie for a flow of fluid longitudinally through all the banks in succession in a reverse direction to the flow through the chambers; and closures for the outer ends of the end shells mounted for shifting to open position to expose the opposite ends of all of the tubes for cleaning them.

7. A heating apparatus comprising an elongated tubular shell closed at its ends; a pair of longitudinal partitions dividing the interior of said shell into longitudinal chambers including a first chamber, a second chamber, a third chamber and a fourth chamber, in succession around the shell axis; a fluid inlet for the first chamber and a fluid outlet for the fourth chamber both at the same end of the shell; a transverse fluid passage within said end of the shell connecting the second and third chambers; transverse fluid passages between the first chamber and the second chamber and between the third chamber and the fourth chamber, both located within the opposite end of the shell; four banks of tubes, each bank extending through one of said chambers, leaving a surrounding conduit space along the latter and opening through the closed ends of the shell; a pair of end shells attached to the opposite ends of the in-

termmediate shell and having the tubes of the four banks opening into them; partitions in the end shell adjacent said inlet and outlet dividing the shell into a chamber opening into the tubes of the fourth chamber and having a fluid inlet, a chamber opening into the tubes of the first chamber and having a fluid outlet, and a chamber opening into the tubes of the second and third chambers; and a partition in the other end shell dividing it into a chamber opening into the tubes of the first and second chambers and a chamber opening into the tubes of the third and fourth chambers, for continuous counter-flow of two fluids throughout the apparatus.

8. A heating apparatus comprising an elongated tubular shell closed at its ends; a pair of longitudinal partitions dividing the interior of said shell into longitudinal chambers including a first chamber, a second chamber, a third chamber and a fourth chamber, in succession around the shell axis; a fluid inlet for the first chamber and a fluid outlet for the fourth chamber both at the same end of the shell; a transverse fluid passage within said end of the shell connecting the second and third chambers; transverse fluid passages between the first chamber and the second chamber and between the third chamber and the fourth chamber, both located within the opposite end of the shell; four banks of tubes, each bank extending through one of said chambers, leaving a surrounding conduit space along the latter and opening through the closed ends of the shell; a fluid inlet for the tubes of the fourth chamber near the said chamber outlet; a fluid outlet for the tubes of the first chamber near said chamber inlet; a transverse passage connecting the tubes of the second and third chambers at the end of the shell having said inlets and outlets; a passage connecting the tubes of the first and second chambers; and a passage connecting the tubes of the third and fourth chambers, said latter passages being at the opposite end of the shell, for continuous counter-flow of two fluids throughout the apparatus.

In testimony whereof I hereunto affix my signature.

50 SAMUEL H. McKNIGHT.
